UNITED STATES PATENT OFFICE.

JOHN E. BLAKE AND CHARLES A. HALL, OF NEW YORK, N. Y.

ELECTRICAL LOW-WATER ALARM.

SPECIFICATION forming part of Letters Patent No. 286,581, dated October 16, 1883.

Application filed January 26, 1883. (No model.)

To all whom it may concern:

Be it known that we, JOHN E. BLAKE and CHARLES A. HALL, of the city, county, and State of New York, have invented a new and useful Improvement in Low-Water Indicators; and we do hereby declare the following to be a full, clear, and exact description of the same, reference being had to the accompanying sheet of drawings, forming part of this specification.

This invention is in the nature of an improvement in electrical low-water alarms for steam-boilers; and the invention consists in the following elements in combination, as hereininafter more particularly set forth and claimed, viz: a thermometer-tube of mercury with platinum wires inserted at given points through the sides thereof into the inner channel of the thermometer, the tube of the thermometer being provided with a bulb for the mercury at its lower end and a reservoir-bulb at its upper end; the bulb at its lower end having a perforated guard around it; a gland formed at one end of a tube, into which tube is fitted a gage-cock; an air-tube within said gland; the current-wires of an electric battery connecting said thermometer-tube with the cells of a battery and an alarm-bell; a guard-tube enclosing the thermometer-tube, and an insulated cap fitted in the upper end of said guard-tube.

In the accompanying sheet of drawings, Figure 1 is a longitudinal section, showing alarm device attached to a steam-boiler. Fig. 2 is a cross-section of the gage-cock and tube, taken in line *x* and *y*, Fig. 1.

Similar letters of reference indicate like parts in the several figures.

The importance of having an infallible indicator to give warning when the water in a steam-boiler has reached a dangerous level has been recognized ever since the introduction of steam-boilers into general use, and for that purpose numerous contrivances have been adopted, mainly, however, in the nature of plugs of a metallic alloy that would fuse at steam temperature, and allow the escaping of steam to sound an alarm of some kind; but it is difficult to make alloys of metal that will with certainty fuse at the temperature required, owing to the varying purity of the

metal composing the alloy; hence, as a rule, low-water indicators of that and every similar kind cannot be relied upon implicitly. It is believed, however, by our invention, that an infallible means for indicating low water in a boiler is obtained. To that end we construct the thermometer-tube *A* with a bulb, *a*, at its lower end containing mercury, and a reservoir, *b*, at the upper end of said tube. Through the sides of the thermometer-tube, and passing into the mercury-channel within the same, are inserted two platinum wires, *B* and *C*. The lowermost wire, *C*, is inserted at a point which will indicate the temperature of boiling water— 212° —and the uppermost wire, *B*, is inserted at a point which will indicate the average temperature of steam, or, say, 220° to 240° . This thermometer-tube has its bulb *a* surrounded by a perforated guard, *D*. The guard and the bulb *a* of the thermometer pass into a gland or reservoir, *E*, in which position it is firmly fixed by means of suitable screw-collars, *d* and *e*, or otherwise. The reservoir *E* is at the outer end, and forms part of a tube, *F*, which tube, at its inner end, is firmly screwed either in the face of a boiler, *G*, or some of its connections.

Into the tube *F*, and near the face *G* of the boiler, is inserted an ordinary gage-cock, *f*. From the interior of the boiler, and passing through the tube *F* into the reservoir *E*, is an air-tube, *H*. Surrounding the thermometer-tube *A*, and secured at its lower end to the collar *e*, is a protecting shell or tube, *K*, and into the upper end of this protecting-tube is inserted and securely fixed an insulated cap, *L*, of hard rubber or other insulating material, through which cap pass the upper ends of the wires *B* and *C*. Into the insulated cap *L* are inserted the ordinary binding-screws, *g*, which connect the wires *B* and *C* with the current-wires *h* of an ordinary galvanic battery and electric alarm-bell, *m*. Now, when the tube *F* is screwed into the face of a steam-boiler or some suitable connection of the same at a point where it is inserted by the lowermost of the three ordinary gage-cocks, and the boiling water, at a temperature 212° , passes from the boiler into the tube *F* and into the reservoir *E* of said tube, it at once surrounds the bulb *a* of the thermometer-tube *A*, caus-

ing the mercury therein to ascend until brought in contact with the inserted wire C, which temperature represents, as before stated, the boiling-point of water, and since the mercury at this temperature can ascend no higher than 212°, there is no connection between the wires C and B, the electric circuit remains broken, no alarm is sounded, and the engineer is aware that the crown-sheets of his boiler are well 10 covered with water, or that the water in the boiler is not dangerously low; but should the water within the boiler fall below the mouth of the tube F, steam, instead of water, will enter through that tube into the reservoir E, 15 causing by its increased temperature the mercury within the thermometer-tube A to ascend in this tube until it reaches the average temperature of steam—say 220° or 240°—at which point it strikes the inserted wire B and forms 20 a metallic connection between the wires B and C, completing the electric circuit, causing the alarm-bell M to be rung, and this alarm continues to ring until sufficient feed-water has been introduced into the boiler and has again 25 entered the tube F and reservoir E, reducing the temperature and causing the mercury to drop or descend from the temperature of steam to the temperature of boiling water, thereby breaking the connection between the wires B 30 and C in the manner stated, when the bell will cease ringing. Now, when the boiler is first filled with water, as the water enters the tube F the air within the tube and reservoir, if no escape is provided, will tend to keep out 35 the water from the reservoir and also surround the bulb of the thermometer, and being a non-conductor to some extent, it will interfere with the prompt action of the device. Therefore we insert within the tube F and reservoir E 40 an air-tube, H, through which last-named tube the air passes as the water enters the tube F.

To protect the bulb *a* of the thermometer from breaking from the force of the entering 45 steam, or from being broken by coming in contact with the tube H, we inclose this bulb in a perforated guard of metal, D, and to prevent the accidental breaking of the thermometer-tube A a shell or tube, K, is placed over 50 it, and held in place by being screwed to the collar or nut *e*. That the current of electricity from the battery may not be diverted by coming in contact with the protecting-tube K, an insulated cap, L, is fixed to the upper 55 end of the tube K, through which the wires *h*, B, and C pass, and are united by means of binding-screws *g*. As it frequently happens, the temperature of steam in the boiler is greater than that of 220°, or the point at which the

uppermost wire B is inserted. This increased 60 temperature will drive upward the column of mercury in the tube until it impinges with such force at the upper end of the tube as to fracture the thin glass bulb at its lower end. To obviate this, a small reservoir, *b*, is blown 65 in the upper end of the thermometer-tube A, which will receive the surplus mercury as it is forced upward, and relieve the bulb from pressure.

Having now described our invention, what 70 we claim as new, and desire to secure by Letters Patent, is—

1. In an electric low-water indicator or alarm, the following elements in combination: a thermometer-tube A, with a bulb, *a* at its 75 lower end and a reservoir, *b*, at its upper end, with platinum wires B and C inserted through the sides of said tube; a reservoir, D, tube F connecting said reservoir with a steam-boiler; an air-tube, H, within said tube F; a protecting-tube, K, with an insulated cap, L, fitted in the upper end thereof, and current-wires *h*, 80 passing through said insulated cap and connected with the platinum wires B and C, and a galvanic battery and electric bell, all arranged and constructed as and for the purpose described.

2. In an electric low-water alarm, the combination of a gage-cock with the tube F, reservoir E, and thermometer-tube A, as and for 90 the purpose described.

3. In an electric low-water alarm, the tube F, with a reservoir, E, at its outer end, in combination with an air-tube, H, and thermal connections with an electric-alarm mechanism, as 95 and for the purpose described.

4. In an electric low-water alarm, the combination of the gage-cock *f* and the pipe F with a thermometer, A, wires B and C, inserted in the sides thereof, and a galvanic battery 100 and alarm-bell, as and for the purpose described.

5. In an electric low-water alarm, the thermometer-tube thereof, in combination with a perforated guard, D, surrounding its bulb, 105 and a reservoir, *b*, at its upper end, as and for the purpose described.

6. In an electric low-water alarm, the combination of a tube, K, and an insulated cap, L, with the wires *h* and B and C, a thermometer-tube, the tube F, and an electrical battery and alarm-bell, as and for the purpose described.
